Thomas J. Brawley, Jr., Gastonia, N.C., assignor to Pyramid Dye Corporation, Bessemer City, N.C., a corporation of North Carolina

Filed June 4, 1965, Ser. No. 85,572

Term of patent 14 years

(Cl. D92—15)

FIG. 1.

FIG. 2

FIG. 3

FIGURE 1 is a top perspective view of a hand loom showing my new design, the side opposite being identical thereto.

FIGURE 2 is an enlarged vertical sectional view taken substantially along the line 2—2 in FIGURE 1 and showing a fragmentary portion of the adjacent wall of the hand loom in elevation;

FIGURE 3 is a fragmentary sectional view of the hand loom similar to FIGURE 2 but taken substantially along the line 3—3 in FIGURE 1.

The bottom of the hand loom is of a planar configuration and unornamented.

I claim:

The ornamental design for a hand loom, as shown and described.
